(57) **CLAIM**

The ornamental design for a non-marking interlocking strap device, as shown and described.

DESCRIPTION

FIG. 1 is a front view of the non-marking elastic strap device embodying our new design,

FIG. 2 is an enlarged right side view thereof,

FIG. 3 is a rear view thereof,

FIG. 4 is an enlarged left side view thereof,

FIG. 5 is a top view thereof,

FIG. 6 is a bottom view thereof; and,

FIG. 7 is a perspective front view of the non-marking elastic strap device of the present invention.
